Des. 70,868

UNITED STATES PATENT OFFICE.

WESTERN UNDERWOOD, OF SANTA ANA, CALIFORNIA.

DESIGN FOR A STREET LAMP.

Application filed September 9, 1924. Serial No. 10,714. Term of patent 7 years.

To all whom it may concern:

Be it known that I, WESTERN UNDERWOOD, a citizen of the United States, residing at Santa Ana, in the county of Orange and State of California, have invented a new, original, and ornamental Design for Street Lamp, of which the following is a specification, reference being had to the accompanying drawing, forming part thereof.

The figure is a perspective view of the street lamp.

I claim:

The ornamental design for a street lamp, as shown.

WESTERN UNDERWOOD.
